RUBBER HEEL

Albert Monti, Medford, Mass.

Application April 28, 1945, Serial No. 590,759

2 Claims. (Cl. 36—39)

1

The present invention relates to the construction of heels, particularly rubber, synthetic rubber or composition heels which may be applied to shoes or more particularly to rubber boots. The present invention is an improvement on my earlier filed copending application, Serial No. 538,269, filed June 1, 1944.

As explained in my prior application, the heel wears more rapidly in some portions, particularly at the back of the heel, than at other parts of the heel. The applicant has overcome this difficulty by the use of a heel with a center cylindrical insert which normally extends slightly above the surface of the heel perhaps no more than one-sixteenth of an inch and which is adapted to turn while the wearer is walking on the shoe.

In my prior application above mentioned, provision was made for permitting the heel to turn. However, particularly when such a heel is applied to the rubber boot for use in water under certain circumstances of use, there is less tendency for the heel insert to turn of its own accord. In the present arrangement, however, this difficulty is overcome by using the proper elements which reduce the friction between the insert and the heel base so that the heel insert will readily turn even under uniform pressure of soft material such as, for instance, mud in which boots may be used.

A further advantage of the present invention is that the arrangement described herein is particularly useful in combination with a rubber boot where the heel must at all times be sealed and nails, spikes or other joining members cannot readily be used to attach the heel to the boot.

Further advantages of the present invention will more readily appear from the construction and details of the invention as set forth in the specification below in connection with the drawings illustrating an embodiment of the same in which:

Figure 1 shows an exploded view of the heel and boot with the heel indicated in section and

Figure 2 shows a plane view of the heel looking upward as referred to Figure 1.

In the arrangement shown in the figures, the boot 10 has the heel 11 vulcanized to it along the joining base 12. The heel 11 is recessed with a cylindrically shaped recess 13 which, as indicated in Figures 1 and 2, is located toward the back of the heel, providing a comparatively thin rear wall heel portion as indicated at 14. The recess 13, which is cylindrical in shape, may be approximately one-fourth of an inch thick, sufficient to extend just above the bottom surface

15 of the heel which is uniform and flat over its whole surface. Within the cylindrical recess 13 there is normally positioned the cylindrical insert 3 which fits sufficiently freely so that it does not bind on the sides and may, therefore, turn. The cylindrical insert is attached to the base by means of a pivot joint which will permit it to turn easily when worn. This is accomplished by moulding in the base 11 of the heel a stud 6 which is provided with an enlarged projecting flange 8 imbedded in the heel. The stud 6 projects slightly above the inner surface 17 of the recess as indicated at 16. A shoulder 18 and a neck section 19 is formed as an integral part of the exposed end of the stud 6. The stud is tapped and threaded in a central recess 20 to receive the machine screw 4 which is provided with a large head 5 which holds the insert 3 in place, as will be explained. The insert 3 has also moulded into it a collar or bushing 1, the internal diameter of which is such that the bushing fits freely over the neck 19 to permit it to turn. The bushing 1 is anchored in the insert 3 by an extending flange or spider 2 which anchors the bushing firmly in the insert concentric with the insert itself. The head of the machine screw 4 is of such diameter that it covers over the end of the bushing and may be tightened through the bottom hole 24 in the lower face 25 of the insert 3.

30 In the assembly of the heel the insert 3 is brought down over it with the bushing fitting over the neck 19 and the end of the bushing bearing against the shoulder 18. The machine screw 4 is put on tightly so that the end of the bushing 35 1 will be brought against the shoulder 18. The stud 6 is not made to project beyond the surface 17 so that the inner surface 26 of the insert 3 is brought flush with the surface 17, the end of the bushing 1 still resting and bearing on the face 18 of the stud.

I claim:

1. In combination with a shoe having a rubber heel, the face of which is circularly recessed at the back of the heel forming a thin back wall, a cylindrical rubber insert adapted to fit for free rotation in the recess of the heel and project slightly below the surface of the heel, said heel having molded therein concentric with the recess a fixed metallic stud having a circular shoulder and a terminating neck portion projecting beyond the base surface of the recess, said cylindrical rubber insert positioned to bear on the base surface of said recess and having molded therein a bushing concentric with the insert and adapted to fit over said neck portion, the inner end of the

bushing bearing against the face of said shoulder and a screw having a large head bearing against the exposed end of the bushing and threaded concentrically into said stud.

2. In combination with a shoe having a rubber heel, the face of which is circularly recessed at the back of the heel forming a thin back wall, a cylindrical rubber insert adapted to fit for free rotation in the recess of the heel and project slightly below the surface of the heel, said heel having molded therein concentric with the recess

a fixed metallic stud having a circular projecting portion projecting beyond the surface of the recess, said cylindrical rubber insert positioned to bear on the base surface of said recess and having moulded therein a bushing concentric with the insert and adapted to fit over said projecting portion, the projecting portion being threaded and a screw having a large head bearing against the exposed end of the bushing when the screw is made to engage said projecting portion.

ALBERT MONTI.
